HAND GUN CYLINDER CONTROL AND
TRIGGER MECHANISMJohn H. Gartner, San Francisco, Calif., assignor
to Samuel I. Keene, San Francisco, Calif.

Application June 21, 1948, Serial No. 34,189

16 Claims. (Cl. 42—66)

1

This invention relates to hand guns and has for one of its objects the provision of improved means for controlling the cylinder of a revolver so that a loaded chamber in the cylinder will be held in alignment with the barrel upon a retraction of the hammer or the like immediately following an uncocking of the hammer and its release.

Heretofore in revolvers, the cylinder is revolved to align one of its cartridge holding chambers with the barrel immediately prior to bringing the hammer to a full cock, whether the hammer is retracted by the thumb or whether it is retracted by pressure on the trigger, as in double action firing.

If the hammer is cocked and then is released or is let down by the thumb, the next retraction of the trigger or cocking of the hammer will cause the cylinder to revolve so as to bring the next chamber into alignment with the barrel.

The above action is desirable where the hand gun is fired after each retraction of the hammer or trigger, but it is obvious that the not infrequent occurrence of firing say four shots (assuming the cylinder is loaded with five cartridges only) will leave the user with a cocked hammer over the final loaded cylinder which may not require firing at the moment, due, for example, to the surrender of the law breaker or suspect or to feigned incapacitation or to actual temporary incapacitation. Under such circumstances, the person using the hand gun is faced with the choice of letting down the hammer of the gun for safety reasons or in retaining it cocked with the chance of injuring himself or innocent bystanders. If the hammer is let down, it will require five complete firing operations or retractions of the trigger before the only loaded chamber is brought into alignment with the barrel again.

With the present invention, the person using the revolver is enabled to let the hammer down and to release the trigger without causing the cylinder to be rotated upon the next retraction of the trigger or hammer or both.

Another object of the invention is the provision of improved and relatively simple means for effecting the release of the cocked hammer in a hand gun upon a release of the finger retracted trigger, including means associated with the trigger and positioned for actuation by the trigger actuating finger when the latter is in a position holding the trigger retracted for preventing the

2

firing of the hand gun upon such release of the retracted trigger, when desired.

A still further object of the invention is the provision of improved safety means in a hand gun of the type in which the hammer is released for firing upon release of the trigger from a retracted position.

An added object of the invention is the provision of means associated with the conventional trigger and firing mechanism of a hand gun for converting such mechanism into one in which the hammer is held in cocked position by the trigger finger when the latter is retracted and is quickly and easily released for firing upon a release of the pressure of the trigger finger on the trigger.

In using hand guns, such as revolvers and pistols, accurate shooting is usually considerably more difficult than in using a rifle. Where no rest is employed, one hand fully supports the weight of the hand gun while the trigger finger of such hand retracts the trigger. Usually years of at least weekly practice of relatively long duration is required to attain recognized proficiency, and even then many persons will still be mediocre marksmen.

Practice sessions, in order to reach proficiency in shooting, are mainly devoted to the so-called "trigger squeeze" in which the trigger is supposed to be slowly retracted only during those moments when the sights are correctly aligned with the bull's-eye on the target. If the trigger is suddenly yanked or pulled as the front sight wavers across the bull's-eye, in the hope of hitting the latter, the sights will in all likelihood be pulled off the target to the right, looking at the target (if the shooter is right handed), before the cartridge is fired. This is particularly true where the approved pressure of from three to four pounds is required on the trigger in order to release the cocked hammer. Hair set triggers are extremely dangerous and are not permitted in national matches and on most ranges.

In view of the difficulty, time and expense that are required before reasonable accuracy with hand guns can be acquired by the average person, relatively few persons become expert with hand guns. The lives of police officers, soldiers and others whose personal safety may at any time depend upon their ability to use hand guns with reasonable accuracy are many times placed in jeopardy before the years have passed in which the desired proficiency is acquired by conventional methods.

By the present invention adequate proficiency can usually be acquired within a small fraction of the time heretofore required, and in many instances high proficiency has been acquired where heretofore even average proficiency has been deemed unattainable.

The reason for the above is that provision is made for releasing the cocked hammer upon a relatively small release of the trigger when the latter is held in fully retracted position. Inasmuch as there is no sudden tensing of the muscles during a releasing action of the trigger finger, the hand gun will not be pulled off the target, and inasmuch as the hammer is released almost instantly upon a release of the trigger, there is no sustained period of tension. The shooter is enabled to fire the piece instantly when he knows the sights are properly aligned instead of following the usual heretofore recommended practice of not knowing when the firing will occur.

The provision of safety means whereby the user of the gun may quickly let the hammer down in safety if, after a retraction of the trigger, it is decided not to fire the gun, may be accomplished in various ways. In the present instance the safety feature is under the control of the trigger finger. A slight upward pressure of the trigger finger against the trigger when the latter is retracted and the hammer will be safely lowered without requiring the use of the thumb on the hammer. Thus the invention may be embodied in revolvers of the hammerless type.

Other objects and advantages will be seen from the drawings and specification.

In the drawings, Fig. 1 is a side elevational view of a revolver with the cover plate over the near side of the trigger and firing mechanism removed to show the said mechanism. The barrel is cut off to accommodate the view to the sheet and the said mechanism is shown in the normal inoperative position with the hammer down and the trigger forward.

Fig. 2 is a side elevational view of the portion of the revolver of Fig. 1 in which the trigger and firing mechanism is held, the trigger and hammer being retracted. The cylinder turning hand is omitted from this view.

Fig. 3 is a view similar to that of Fig. 2 showing the trigger and firing mechanism immediately after the hammer has been released. The trigger is slightly forward relative to the position of the trigger in Fig. 2.

Fig. 4 is a view similar to that of Fig. 2 except that the cylinder turning hand is shown in position and the safety device on the trigger is moved up to guide the said hand out of engagement with the cylinder upon the next retraction of the trigger.

Fig. 5 is a view similar to that of Fig. 1 but with the trigger forward and the hammer down following actuation of the safety device on the trigger so that a retraction of the trigger will not rotate the cylinder.

Fig. 6 is a view of the hammer cover, in section, removed from the revolver.

Fig. 7 is a rear elevational view of the hammer cover of Fig. 6.

Fig. 8 is a perspective view of one of the elements in the trigger mechanism for causing the cylinder rotating hand to be inoperative in one of the movements of the trigger.

Fig. 9 is a perspective view of a detent element for releasably holding the element of Fig. 8 in

one position or the other during certain movements.

Fig. 10 is a perspective view of a locking element for preventing actuation of the safety device until the trigger is fully retracted.

Fig. 11 is a perspective view of one of the safety elements that is carried by the trigger.

Fig. 12 is a perspective view of the trigger.

Fig. 13 is a perspective view of one of the elements connected with the trigger.

Fig. 14 is an enlarged fragmentary elevational view showing the relationship between certain parts of the trigger mechanism when the trigger and hammer are retracted.

Fig. 15 is a view similar to that of Fig. 14 showing the position of certain parts after the safety device on the trigger has been actuated.

Fig. 16 is a fragmentary side elevational view of some of the trigger and firing elements in a position with the trigger and hammer retracted and ready for firing upon a release of the trigger.

Fig. 17 is a view similar to that of Fig. 16 but after firing when the trigger and hammer are forward.

Fig. 18 is a fragmentary part sectional view showing the cylinder turning hand and the guide for said hand.

Fig. 19 is a view similar to that of Fig. 18 but with the trigger retracted.

Fig. 20 is a view similar to that of Fig. 19 showing the safety device actuated for moving the cylinder turning hand out of engagement with the cylinder.

Fig. 21 is an enlarged fragmentary sectional view taken along line 21—21 of Fig. 14.

Fig. 22 is an enlarged part sectional, part elevational, fragmentary view showing the means for yieldably holding the cylinder turning finger forward.

Fig. 23 is an enlarged fragmentary sectional view taken along line 23—23 of Fig. 14.

For example, the hammer in the present instance has been cut down and enclosed, making a so-called "hammerless" revolver, although this feature is not in any way essential to the functioning of the invention.

The sear on the hammer, the spring for driving the hammer to fire the cartridge and to return the trigger, and other elements are identical with those in the standard Colt revolver.

In the detailed description, the terms "forward," "front," "forwardly," "rear," "rearwardly," etc. which might be used in describing the invention are used with respect to the muzzle or barrel end of the hand gun, which is the forward end, while the butt or stock is at the rear end.

The revolver illustrated in the drawings comprises a frame, generally designated 1, and which frame includes a side piece 2 that is integral therewith at one side of the hammer and part of the trigger mechanism. The stock portion 3, except for removable side pieces providing the hand grip, is also integral with the frame, and while the barrel is removable, it is rigid with the frame.

The frame 1 is cut out adjacent the barrel for the cylinder 4 that is chambered for the cartridges and which cylinder is rotatable about an axis parallel with that of the barrel in the usual manner. Axially projecting ratchet teeth 5 are around the axis of said cylinder at its rear end.

The trigger guard 6 is integral with the frame,

and the portion of the frame between the cylinder and the opening of guard 6 into which the trigger extends carries a pivot 7 about which the trigger 8 is pivoted.

Fig. 12 shows the main trigger detached from the revolver. The trigger 8 is recessed along its forward side and the opposed sides of said recess are formed with forwardly projecting ears 9 through which pivot 7 extends.

The forwardly opening recess in the trigger extends downwardly into the lower finger engaging portion of the trigger and said sides of said recess are formed with upwardly facing corresponding shoulder 10 below ears 9 and above the finger engaging portion of said trigger.

The uppermost end of the trigger terminates in a nose 13 having an upwardly facing surface that is the upper end of the bottom of the forwardly opening recess. This nose 13 is adapted to engage the sear on the hammer for cocking the hammer upon retraction of the trigger.

The sear is indicated at 14 (Figs. 1, 17), said sear being pivotally connected at 15 to the hammer 16 at the forward side of the hammer. A spring 17 yieldably urges the lower end of the sear away from the hammer to the full extent of the swing of the sear in a forward direction. The lower end of the sear is swingable rearwardly against the tension of the spring. The above structure is conventional in a Colt revolver.

Pivotedly secured at 18 to the trigger 8 at a point at about the same level as the shoulders 10 is the forward end of an auxiliary locking lever 19. This lever 19 is adapted to slide at its rearwardly extending free end on the lower flange 20 of frame 1. The auxiliary locking lever 19 is shown in Fig. 13 separate from the revolver, and in Fig. 1 it is shown at the start of a cocking action, in which it will be moved rearwardly during the cocking action and at the same time it is moved rearwardly (due to retraction of the trigger), the forward end will move sharply upwardly.

In Fig. 12, the openings 23 in the trigger are for the pivot 18 that connects the forward end of the auxiliary locking lever 19 to the trigger.

The upper side of the lever 19 is formed with an upwardly and rearwardly slanted surface 24 and a flat upper surface 25 extends rearwardly from the lower end of surface 24 to the free end of the lever. The forward rounded end 26 of a locking lever 27 is adapted to be supported on said flat surface 25 (Figs. 16, 17). The rearward end of said locking lever 27 is pivoted at 28 to the frame of the revolver.

Upon retraction of the trigger 8, the auxiliary locking lever 19 will be slid rearwardly on flange 20 of the frame 1. The forward rounded end of the locking lever is slidable on surface 25 during said rearward movement of the lever 19. When said lever 19 is retracted to the point where the upwardly inclined surface 24 extends upwardly from surface 25, the said rounded end 26 will quickly slide upwardly over said surface and this upward movement is augmented or accelerated by the bodily upward swing of the forward end of said lever 19.

In Figs. 1, 17 it is seen that the nose 13 of the trigger will engage the lower end of sear 14 when the trigger is retracted and continued retraction of the trigger will cause the hammer to be cocked or to swing about pivot 31 that secures the hammer to frame 1 for swinging thereabout.

Fig. 16 shows the trigger fully retracted and in

this view it will be seen that the rounded heel 33 of the hammer has been moved to a position slightly forwardly of the inclined surface 24 of lever 19, and that the forward rounded end of the locking lever 27 has been elevated behind said heel so that the engagement between said heel and said rounded forward end of the locking lever prevents the hammer from falling.

Simultaneously with movement of the locking lever to the position holding the hammer cocked, the nose 13 of the trigger becomes disengaged from the sear 14 so that the hammer is solely held by the locking lever 27. However, as soon as the pressure on the trigger is released so it can move forwardly, it will be seen that the forward rounded end 26 of the locking lever 27 will quickly descend on inclined surface 24 and its descent will be hastened by the bodily downward movement of the forward end of lever 19 and the hammer will be released for falling under the tension of spring 33. The hammer pivot is at 31.

This spring 33 (Fig. 1) serves the double function of moving the trigger forwardly and of driving the hammer during its firing stroke. The return of the trigger from retracted position is effected by an arm 34 (Fig. 1) that is pivoted at 35 at its rear end to the portion of frame 1 that extends into the stock of the revolver. The forward end of said arm is slanted at 36 to engage the generally upwardly facing side of a pivot 37 (Figs. 1, 12) that is rigid with the trigger 8 at a point below the nose 13 and relatively close to the latter. Arm 34 is broken away in Figs. 2 to 5 in order to expose the other parts.

Spring 33 is a leaf spring of generally U-shape with its apex secured in a recess in frame 1 at a point just above pivot 35. One arm 38 of the spring engages the upper side of the arm 34 while the other arm 39 of the spring engages the underside of a horizontal projection 40 that is rigid with the hammer 16 and that is rearwardly of the hammer pivot 31. The spring arms, being under tension and tending to spread apart will yieldably hold the hammer down and the trigger forward at all times. This spring and its action are not new, but appear on the standard Colt revolver.

The opposed sides of the part of the forwardly opening recess in trigger 8 extend downwardly into the finger engaging portion of the trigger and a pivot 43 is carried by the sides in said portion. This pivot 43 carries the main control element generally designated 44 (Fig. 11) that is adapted to be manipulated by the trigger finger of the operator for safely lowering the hammer and for preventing rotation of the cylinder upon a retraction of the trigger after a safe lowering of the hammer.

The element 44 has a curved downward extension 45 that follows the contour of the finger engaging portion of the trigger, and pivot 43 pivotally secures said projection to the trigger.

Above the pivot 43 and adapted to lie above the trigger finger of an operator when such finger is in trigger retracting position is a forwardly extending projection 46. This projection is relatively thick in vertical and horizontal dimensions, its horizontal thickness being greater than that of the remainder of the element so that portions 47 project oppositely laterally outwardly relative to the said remainder as seen in Fig. 11, providing rearwardly facing shoulders at opposite sides of the extension 45 about where the latter joins said forward projection 46.

The said rearwardly facing shoulders at the juncture between the projection 46 and the downward extension 45 of element 44 are of a form providing rearward opening notches 48, one at each side of the element 44, the upper side of each notch being a rearwardly directed wedge shaped portion 49 (Figs. 1, 11).

Centrally of the width of the forward projection 46 of element 44, the said projection is recessed on its upper side at 50 as seen in Fig. 11, which recess opens upwardly and has a flat generally horizontally extending bottom side 53 (Figs. 1, 18) extending into the projection in direction toward its forward end, the forward end of this bottom side being formed with a generally rectangular depression or recess 54. The rear side 56 of recess 54 is inclined forwardly from its lower end (Figs. 18 to 20) for a purpose to be described, while the opposite forward side may be square with the bottom or practically so.

Extending upwardly and rearwardly of the element 46 from the rear side of the latter is an arm 57 that is convexly rounded at its outer end at its forwardly facing side as at 58 (Figs. 11, 18), while the rearwardly facing side may be flat, except for a recess 59 that is merely formed in the arm to permit the arm to move to a position in which the pivot 37 extends into the open side of said recess.

Upon retracting the trigger, the outer end of said arm 57 will move upwardly from the position indicated in Fig. 18 to the position indicated in Fig. 19 in which the said outer end will move to a position in a downwardly opening cleft of a member 60 (Figs. 8, 19).

In most revolvers there is a hand or pawl that is pivotally and reciprocably mounted for successively engaging the ratchet teeth 5 of the cylinder 4.

In the present instance this pawl is indicated at 63 (Figs. 1, 4, 5) and extends generally vertically with its lower end pivoted on the pivot 37 that is rigid with the trigger. The upper end of this pawl has a tooth 64 that is adapted to engage the teeth 5 on the rear end of cylinder 4 in succession upon repeated retractions of the trigger. A spring 65 in the cover plate 66 of the near side of the frame as seen in the drawings (Fig. 22) is adapted to urge a follower 67 against the rear edge of the pawl 63 for yieldably holding the same against a flange 68 on frame 1 that extends vertically partially along the rear side of the cylinder (Figs. 1, 14).

As the trigger is retracted the pawl slides upwardly and the tooth 64 engages one of the teeth 5 of the cylinder, rotating the same until the cartridge in the next chamber is aligned with the barrel. This alignment occurs before the hammer is released, so that the bullet will be properly ejected from the chamber into the barrel when the cartridge is fired. When the trigger is released to move forwardly, the pawl 63 will descend and upon the next retraction of the trigger the cylinder will again be rotated.

The member 60 is formed with a pivot 69 for pivoting said member on the frame of the revolver (Figs. 8, 14). Said member 60 also is formed with a rearward projection 70 that in turn has a laterally opening generally U-shaped recess 73 in the near side as seen in Figs. 14, 21.

A flat spring 74 (Fig. 21) lies between the cover plate 66 and the frame 1 and has a pin 75 on one end that fits in a corresponding recess in frame 1, while the opposite end has a detent 76 that is adapted to either lie in the recess 73 or to lie

against the slanted surface 77 (Fig. 21) adjacent said recess according to the way the member 60 is swung on its pivot. This detent 76 functions merely to hold the member 60 in one of its two positions until it is swung forcibly to the other position.

For example, upon retraction of the trigger 8, the cylinder will be rotated by the pawl 63, but should the user decide not to fire the piece but to let down the hammer gently without firing, he will merely exert a slight upward pressure of the trigger finger against the projection 46 and the arm 57 will be swung rearwardly at its outer end. As said arm is in the cleft of the member 60 when this occurs, as seen in Fig. 19, the rearward swing will cause the cleft to swing rearwardly to the position seen in Fig. 20.

Member 60 has a lateral projection 78 that normally lies in upward extension of flange 68 on which pawl 63 is slideable, and when the member 60 is swung rearwardly by arm 57 as above explained, the said projection 78 will move rearwardly of flange 68 a sufficient distance to prevent the tooth 64 on the pawl from engaging the teeth 5 on the next upward movement of the pawl. Detent 76 will move into recess 73 when said member 60 is swung rearwardly so as to hold the projection 78 in a position to guide the pawl 63 away from the teeth 5 (Figs. 2, 15).

However, upon the second retraction of the trigger, the convex rounded end of the arm 57 will engage the forward side of the cleft on the member 60 and will swing the projection 78 forward so that detent 76 will again rest on the surface 77 of the projection 70 and will hold the projection 78 forward in line with flange 68 until and unless the projection 46 on the control element 44 is again moved by the trigger finger.

This control element 44 also functions to enable the operator to let the hammer down by the trigger finger without firing the revolver.

This release is effected by the arm 57. In Fig. 15 it will be seen that arm 57 has been swung rearwardly to a position swinging the member 60 so that projection 78 will guide the pawl away from the ratchet teeth 5 when the trigger is again retracted after being released by letting down the hammer. The outer end of the arm 57 in Fig. 15 now lies under a forwardly projecting nose 79 at the lower side of the hammer and forwardly of the hammer pivot.

A release of the trigger from the position seen in Fig. 15 will permit the nose 73 on the trigger to pass between the sear and the nose 79 on the hammer. Thus, while the load of the hammer will be taken by arm 57 to gently lower the hammer as the trigger is released, the trigger nose 73 will be in a position to also prevent falling of the hammer to fire the cartridge, thereby providing a double safety feature for the hammer cannot freely fall if the nose 73 is below the sear.

In order that the hammer cannot be accidentally released by any inadvertent movement of the forward projection 46 until the trigger is fully retracted, a locking element 80 is provided (Fig. 10), which element is pivotally secured to the frame 1 of the revolver by trigger pivot 7 (Fig. 18).

This element 80 is between the ears 9 of the trigger and has a spring 83 projecting from one side of said element in frictional engagement with one of said ears so that the element will be frictionally held in any position it may be moved with respect to the ears 9.

The element 80 is flattened and has an upper

straight edge 84 that extends rearwardly relative to pivot 7. This edge is adapted to engage a horizontal flange 85 on frame 1 below cylinder 4 when the trigger is retracted to limit the swinging of the element 86 on pivot 7 although the trigger may continue its rearward movement about said pivot (Fig. 19).

The lower edge of the locking member has a downwardly projecting lug 86 therein that is adapted to enter the recess 54 in the forward projection 46 of the control element 44 when said trigger is fully retracted and the lug 86 is in register with said recess. However, unless the trigger is fully retracted the lug cannot enter said recess and consequently the projection 46 cannot be swung upwardly by the trigger finger.

The rear side of lug 86 is inclined to correspond with the inclined rear side 56 of recess 54, hence as the trigger moves forwardly the lower end of the locking member will move forwardly with it to the position seen in Fig. 18 when the lug will move out of recess 54.

In operation, the user of the revolver fully retracts the trigger, thus moving the hammer to cocked position in which it is held by the pressure of the trigger finger on the trigger. Aim is taken and the instant the sights are aligned on the target, a slight release of the trigger will result in releasing the hammer and in firing the piece.

If the user does not wish to fire the piece after having retracted the trigger, a slight upward movement of the trigger finger will result in enabling the hammer to be let down with the forward movement of the trigger, and at the same time the projection 78 will be moved out of its normal position to prevent rotation of the cylinder during the next retraction of the trigger.

It is obvious that this means for preventing the rotation of the cylinder is applicable to a mechanism in which the hammer is released by a retraction of the trigger as well as one in which the hammer is released by release of the trigger. In the present instance the mechanism has been cooperatively associated with the means for releasing the hammer by a release of the trigger.

As has been noted, in the present case the hammer is released upon very slight forward movement of the trigger, thus virtually giving the shooter all of the advantages of a hair trigger and with perfect safety. Inasmuch as the hammer cannot be released until there has been a full retraction of the trigger, accidental discharge is prevented except under such abnormal circumstances as are practically non-existent. The pull in pounds required to fire the revolver is the same as in the standard firearm and meets all of the requirements for shooting in the national matches.

It is also to be noted that with the arrangement shown in which the element 46 is prevented from upward movement until the trigger is fully retracted, there can be no accidental actuation of the member 60 that would prevent a rotation of the cylinder on the next retraction of the trigger. It is highly important that the cylinder be turned after each shot is fired, but it should not be turned when a loaded unfired chamber in the cylinder is in alignment with the barrel.

In Figs. 1 to 7, a cover 90 is shown over the hammer. Obviously the hammer could be exposed if desired, and formed in the conventional manner for thumb engagement, but inasmuch as the trigger mechanism in the present instance is arranged so that the trigger finger may be used to gently let down the hammer from cocked posi-

tion, and as the pressure of the trigger finger on the trigger holds the hammer against release thereof, there is no particular advantage to be gained by exposing the hammer.

5 The cover 90 is provided at one end with a projection 91 that releasably fits in the usual opening in the frame 1 in which the upper end of the hammer operates while a screw (not shown) in frame 1 extends into a side recess 92 in a projection 93 at the other end of the cover thereby retaining the cover in place.

Upon retraction of the trigger from the normal uncocked condition of the revolver, the nose 13 on the upper end of the trigger will cause a retraction of the hammer by reason of said nose being in engagement with the sear 14, and at the same time, the upper toothed end of pawl 63 will engage one of the ratchet teeth 5 on the cylinder 1 to cause rotation of said cylinder until the next 20 chamber in said cylinder is in alignment with the barrel.

The retraction of the trigger also causes the lever 19 to be moved rearwardly on flange 20 of frame 1 and as soon as the heel 30 of the hammer 25 has moved, during its retraction, to a position slightly forwardly of the inclined surface or shoulder 21 of lever 19, the forward rounded end of lever 27 will engage said shoulder 21 and will move upwardly behind the heel 30 of the hammer. Substantially simultaneously with this movement of the forward end of lever 27, the nose 13 on the upper end of the trigger will become disengaged from the sear 14, and the hammer will be held retracted or cocked by the elevated forward end of lever 27.

In order to fire the revolver, when it is in the above position, the trigger is released so it will move forwardly and when this occurs the lever 19 being connected with the trigger will also move forwardly and the elevated forward end of lever 27 will be released to slide down the inclined shoulder 24 on lever 19 and away from the heel 30 of the hammer, thereby releasing the hammer for firing the cartridge. After such firing the revolver will again be in exactly the same position 45 it was at the start, and the cycle will be repeated upon retraction and release of the trigger in the manner above described.

Should the user have fully retracted the trigger to the point where a release of the same would 50 result in a release of the hammer, and he then decide not to fire the revolver, said user merely moves the trigger finger upwardly against the projection 46 of element 44, said projection being immediately above the trigger finger.

55 The upward pressure of the trigger finger on said projection will cause the entire element 44 to swing on pivot 43. The projection 46 extends generally forwardly of said pivot while an arm 57 extends generally upwardly therefrom. Hence, 60 upward swinging of the upwardly extending arm 57, and when said arm 57 swings rearwardly, its upper end will move below a forward projection 79 on the lower forward part of the hammer to thereby hold the hammer from falling when the trigger is released. At the same time, the upper end of arm 57 will swing a member 60 rearwardly to cause a projection 78 to engage the pawl 63 and to swing the upper toothed end of said pawl 70 a sufficient distance away from the teeth 5 on the cylinder 4 to prevent its engagement with said teeth when the trigger is retracted after its release. This member 60, when swung by a detent 76 that engages the same until it is forced back to its first position.

The forward movement of the trigger will result in the hammer being carried down to its forward position by the arm 57 that is in engagement with the projection 79 on the hammer. As the trigger moves forwardly the nose 13 of the same will move back to its position below sear 14 so that the hammer would be prevented from firing the cartridge in the cylinder even if the arm 57 should slip from the projection 79 during the forward movement of the firing pin that is on the hammer.

When the trigger is fully released and the hammer is down, the projection 78 on member 60 is still in a position to prevent the upper toothed end of pawl 63 from engaging the tooth 5 on cylinder 4 that would cause rotation of the cylinder, and upon the initial retraction of the trigger, the upper end of the pawl will not engage said tooth 5, but will move past the tooth, and then the upper end of arm 57 will move upwardly into the downwardly opening cleft in member 60 and as the said arm 57 cannot swing rearwardly on its pivot 43 until the trigger is fully retracted, the said upper end of the same will force the member 60 back to its normal position where projection 78 will not act to prevent the engagement between the upper end of the pawl 63 and the tooth 5 on the cylinder when the trigger is released for another firing of the revolver, provided, of course, the revolver is fired. No matter how many times the trigger is retracted, the cylinder will not be revolved upon each successive retraction unless the revolver is fired. If the hammer is let down by reason of upward movement of the projection 46 by the trigger finger, the next retraction of the trigger will not revolve the cylinder.

As already mentioned, the projection 46 and arm 57 cannot be swung on pivot 43 until the trigger is fully retracted, since the lug 86 on the element 80 must be in register with the recess 54 in the element 44 before the latter, which has projection 46 thereon, can be swung on pivot 43.

I claim:

1. In a revolver including a retractable trigger, a revolvable cylinder and a cylinder rotating member connected with said trigger for actuation thereby and movable into engagement with said cylinder for rotating said cylinder at each retraction of the trigger, means supporting said member for movement relative to said trigger to a position out of engagement with said cylinder, an element carried by said revolver and supported for movement to a position in engagement with said member for holding said member out of engagement with said cylinder during said retraction of said element.

2. In a revolver including a retractable trigger, a revolvable cylinder and a cylinder rotating member connected with said trigger for actuation thereby and movable into engagement with said cylinder for rotating said cylinder at each retraction of the trigger, manually actuatable means connected with said trigger for movement therewith during its retraction and supported on said trigger for movement independently of the retractive movement of said trigger, means supported for movement to a position holding said member out of said cylinder engaging position, said last mentioned means being movable to said position by said manually actuatable means upon actuation of said manually actuatable means after retraction of said trigger.

3. In a revolver including a retractable trigger, a revolvable cylinder and a cylinder rotating member connected with said trigger for actuation thereby and movable into engagement with

said cylinder for rotating said cylinder at each retraction of the trigger, and means on said revolver accessible to the trigger finger of the hand when the latter is in a position holding the trigger in retracted position for moving said member out of cylinder actuating position during release of said trigger and the next immediate retraction thereof.

4. In a revolver including a retractable trigger, 10 a revolvable cylinder and a cylinder rotating member connected with said trigger for actuation thereby and movable into engagement with said cylinder for rotating said cylinder at each retraction of the trigger, and means supported on said trigger for movement relative thereto into engagement with said member for moving said member out of cylinder actuating position, said means being positioned adjacent the upper part of the finger engaging portion of said trigger for 20 actuation thereby upon slight upward movement of such finger.

5. In a revolver including a retractable trigger, a revolvable cylinder and a cylinder rotating member actuatable for movement upon each retraction of said trigger for rotating said cylinder, a spring loaded hammer and a sear engageable by said trigger for cocking said hammer against the tension of its spring upon retraction of said trigger, means for holding said hammer cocked 30 upon such retraction, releasable upon release of said trigger whereby said hammer will be released for free falling and for firing of the revolver only upon release of said trigger, and manually actuatable movable means movable to a position 35 obstructing the free falling of said hammer upon said release of said trigger, and means for rendering said cylinder rotating member inoperative during retraction of said trigger immediately succeeding actuation of said manually actuatable 40 movable means.

6. In a revolver including a retractable trigger, a revolvable cylinder and a cylinder rotating member actuatable for movement upon each retraction of said trigger for rotating said cylinder, a spring loaded hammer and a sear engageable by said trigger for cocking said hammer against the tension of its spring upon retraction of said trigger, means for holding said hammer cocked upon such retraction, releasable upon release of said trigger whereby said hammer will be released for free falling and for firing of the revolver only upon release of said trigger and manually actuatable movable means movable to a position obstructing the free falling of said hammer upon said release of said trigger, and means 55 for rendering said cylinder rotating member inoperative during retraction of said trigger immediately succeeding actuation of said manually actuatable movable means, said manually actuatable 60 means being carried by said trigger.

7. In a revolver including a retractable trigger, a revolvable cylinder and a cylinder rotating member actuatable for movement upon each retraction of said trigger for rotating said cylinder, a spring loaded hammer and a sear engageable by said trigger for cocking said hammer against the tension of its spring upon retraction of said trigger, means for holding said hammer cocked upon such retraction, releasable upon release of said trigger whereby said hammer will be released for free falling and for firing of the revolver only upon release of said trigger and manually actuatable movable means movable to a position obstructing the free falling of said hammer upon 75 said release of said trigger, and means for ren-

dering said cylinder rotating member inoperative during retraction of said trigger immediately succeeding actuation of said manually actuatable movable means, said last mentioned means being actuatable by said manually actuatable means.

8. In a revolver including a retractable trigger, a revolvable cylinder and a cylinder rotating member actuatable for movement upon each retraction of said trigger for rotating said cylinder, a spring loaded hammer and a sear engageable by said trigger for cocking said hammer against the tension of its spring upon retraction of said trigger, means for holding said hammer cocked upon such retraction, releasable upon release of said trigger whereby said hammer will be released for free falling and for firing of the revolver only upon release of said trigger, and manually actuatable movable means movable to a position obstructing the free falling of said hammer upon said release of said trigger, and means for rendering said cylinder rotating member inoperative during retraction of said trigger immediately succeeding actuation of said manually actuatable movable means, said last mentioned means being actuatable by said manually actuatable means, and said manually actuatable means being positioned for actuation by the trigger finger of the hand when such finger is in trigger retracting position.

9. In a revolver including a frame carrying a spring loaded retractable hammer and a retractable trigger, means connecting said trigger and hammer for retraction of said hammer against the tension of its spring upon retraction of said trigger, a holding mechanism including an element connected with said trigger for releasably holding said hammer retracted upon full retraction of said trigger and upon said trigger being held by the trigger finger of the operator in fully retracted position, said element being movable to a position releasing said hammer upon forward movement of said trigger from its fully retracted position, and manually actuatable means movable to a position obstructing the free forward movement of said hammer upon said release of said trigger.

10. In a revolver including a frame carrying a spring loaded retractable hammer and a retractable trigger, means connecting said trigger and hammer for retraction of said hammer against the tension of its spring upon retraction of said trigger, a holding mechanism including an element connected with said trigger for releasably holding said hammer retracted upon full retraction of said trigger and upon said trigger being held by the trigger finger of the operator in fully retracted position, said element being movable to a position releasing said hammer upon forward movement of said trigger from its fully retracted position, and manually actuatable means movable to a position obstructing the free forward movement of said hammer upon said release of said trigger, said holding mechanism further including a member interposed between said element and said hammer and slidably engaging said element for movement into holding engagement with said hammer upon final movement of said trigger to its fully retracted position.

11. In a revolver including a frame carrying a spring loaded retractable hammer and a retractable trigger, means connecting said trigger and hammer for retraction of said hammer against the tension of its spring upon retraction of said trigger, a holding mechanism including an element connected with said trigger for releasably

holding said hammer retracted upon full retraction of said trigger and upon said trigger being held by the trigger finger of the operator in fully retracted position, said element being movable to a position releasing said hammer upon forward movement of said trigger from its fully retracted position, and manually actuatable means movable to a position obstructing the free forward movement of said hammer upon said release of said trigger, a cylinder for cartridges rotatable on said frame, a cylinder rotating member actuated for movement into engagement with said cylinder for rotating the latter during said retraction of said trigger, said manually actuatable means including a part movable to a position rendering said cylinder rotating member inoperative during the next succeeding retraction of said trigger after an actuation by said manually actuatable means, and means for preventing actuation of said manually actuatable means until said trigger is fully retracted.

12. In a revolver including a frame carrying a spring loaded retractable hammer and a retractable trigger, means including a sear on said hammer connecting said trigger and said hammer for retraction of said hammer against the tension of its spring upon retraction of said trigger, a cylinder rotatable on said frame, a cylinder rotating member connected with said trigger for movement into engagement with said cylinder upon each retraction of said trigger for rotating said cylinder a predetermined distance, movable means supported for movement to a position for moving said cylinder rotating member out of engagement with said cylinder upon lowering said hammer from its retracted position without firing said revolver, and means for so lowering said hammer.

13. In a revolver including a frame carrying a spring loaded retractable hammer and a retractable trigger, means including a sear on said hammer connecting said trigger and said hammer for retraction of said hammer against the tension of its spring upon retraction of said trigger, a cylinder rotatable on said frame, a cylinder rotating member connected with said trigger for movement into engagement with said cylinder upon each retraction of said trigger for rotating said cylinder a predetermined distance, movable means supported for movement to a position for moving said cylinder rotating member out of engagement with said cylinder upon lowering said hammer from its retracted position without firing said revolver, and means for so lowering said hammer, and means automatically actuated by a subsequent full retraction and release of said hammer by said trigger for restoring said movable means to a position permitting engagement between said cylinder rotating member and said cylinder.

14. In a revolver including a frame carrying a spring loaded retractable hammer and a retractable trigger, means including a sear on said hammer connecting said trigger and said hammer for retraction of said hammer against the tension of its spring upon retraction of said trigger, a cylinder rotatable on said frame, a cylinder rotating member connected with said trigger for movement into engagement with said cylinder upon each retraction of said trigger for rotating said cylinder a predetermined distance, movable means supported for movement to a position for moving said cylinder rotating member out of engagement with said cylinder upon lowering said hammer from its retracted position with-

out firing said revolver, and means for so lowering said hammer, and means carried by said trigger in a position for engagement by the trigger finger of the hand of the operator for actuating said movable means by said finger.

15. In a revolver including a frame supporting a hammer for oscillatory movement between a normal uncocked position and a cocked position and a spring connected with said hammer for constantly urging the same toward said normal position, a finger retractable trigger, means connecting said trigger with said hammer for moving said hammer from said normal position to said cocked position against the tension of said spring upon retraction of said trigger, means actuated by a release of said trigger when the latter is fully retracted for releasing said hammer for movement under the influence of said spring to said normal position independently of said trigger, and manually actuatable means for connecting said hammer with said trigger for controlling the rate of movement of said hammer from said fully cocked position to said normal position in direct proportion to the rate of movement of the retracted trigger to its forward normal position, said manually actuatable means being positioned for actuation by a finger of the hand carrying the trigger finger other than the thumb of such hand.

16. In a revolver including a frame supporting a hammer for oscillatory movement between a normal uncocked position and a cocked position and a spring connected with said hammer for constantly urging the same toward said normal position, a finger retractable trigger, means connecting said trigger with said hammer for moving

said hammer from said normal position to said cocked position against the tension of said spring upon retraction of said trigger, means actuated by a release of said trigger when the latter is fully retracted for releasing said hammer for movement under the influence of said spring to said normal position independently of said trigger, and manually actuatable means for connecting said hammer with said trigger for controlling the rate of movement of said hammer from said fully cocked position to said normal position in direct proportion to the rate of movement of the retracted trigger to its forward normal position, said manually actuatable means being positioned on said trigger for engagement by the trigger finger of the operator when said trigger finger is in trigger retracting position.

JOHN H. GARTNER.
